GEORGE G. BROWN AND MOTT SOUDERS, JR., OF ANN ARBOR, MICHIGAN

METHOD AND APPARATUS FOR IGNITING COMBUSTIBLE MIXTURES

Application filed April 15, 1931. Serial No. 530,270.

This invention relates to method and apparatus for igniting combustible mixtures, and more particularly to a method and apparatus for igniting combustible mixtures in combustion chambers without being accompanied by a shock wave.

The invention has for its object generally an improved method of effecting complete inflammation of combustible mixtures without developing undesirable phenomena, particularly shock waves, and to provide suitable apparatus for accomplishing such end.

More specifically, it is an object of the invention to provide a method of effecting combustion in combustion chambers of the character indicated without the development of traveling pressure phenomena of the character indicated, and to provide means for eliminating or substantially suppressing vibrations or oscillations of appreciable amplitude in the traveling flame and in conjunction with the igniting agent.

A further object of the invention is to provide means for controlling the duration and intensity of ignition, particularly the duration of the electric discharge which ignites the combustible mixture in a combustion chamber.

Other objects of the invention will in part be obvious and will in part appear hereinafter.

The invention accordingly comprises the several steps and the relation and order of one or more of such steps with respect to each of the others, and the apparatus embodying features of construction, combination of elements and arrangement of parts which are adapted to effect such steps, all as exemplified in the following detailed disclosure, and the scope of the application of which will be indicated in the claims.

For a fuller understanding of the nature and objects of the invention, reference should be had to the following detailed description taken in connection with the accompanying drawing, in which:

Fig. 1 shows an oven provided with an elongated combustion chamber adapted for the practice of the present invention;

Fig. 2 is a view partly in plan and partly

diagrammatic showing the combustion chamber of Fig. 1 constructed with igniting means adapted for the practice of the present invention; and

Figs. 3, 4 and 5 show schematically alternate forms of electrical systems for igniting combustible mixtures in the manner indicated in Fig. 2 in accordance with the present invention.

In the industrial arts, it is frequently desirable to generate large quantities of heat in relatively small spaces and in relatively short periods of time. The time interval permitted in many instances is so short that it is conventionally described as "instantaneous." The generation of heat in this manner is required in various types of devices, for example, in heat engines, in internal combustion engines, in certain forms of ovens and in intermittent heating devices. It has been customary where space limitations are essential to employ combustible mixtures as the medium supplying the heat which are ignited by any suitable means, for example, by a hot spot or by the passage of an electric spark.

While the liberation of heat under such circumstances may be said to approach the instantaneous, it is known that there is a definite rate of combustion of the combustible mixtures in closed chambers, which rate is determined by several factors, for example by the pressure, by the presence of foreign agents, and by the character of the igniting agent. When combustion of combustible mixtures is initiated in a local portion thereof, inflammation is propagated throughout the mixture at a definite rate, while accompanied by other phenomena, some of which are of a highly detrimental character, for example, the shock and intense traveling pressure waves, accompanying the flame propagation.

The pressure waves normally developed in explosive mixtures of the character indicated, for example in a mixture of hydrocarbon vapors and air, travel with velocities of an order equal to that of sound, and it has been ascertained that they have an accelerating effect on the rate of inflammation

accompanied by a rise of pressure. It has been observed that when such waves exceed a predetermined minimum amplitude, the rate of rise of pressure is affected by the presence of certain foreign agents, for example the rate is frequently increased by tetra-ethyl lead, when introduced in vapor form with the fuel vapor. Where the waves are small of amplitude, the tetra-ethyl lead has been observed to decrease the rate of rise of pressure in the combustion induced by such waves. It is not easy, however, to distinguish between the rate of rise of pressure in such combustion and the rate of reaction in a normal flame where induced by pressure waves. Decomposition of the foreign agent has been proposed to effect control, but it has been determined that decomposed tetra-ethyl lead will not eliminate sound velocity waves under all practical conditions in combustion of this character. The development of such waves into a pressure wave of relatively great amplitude, or so-called shock wave, has been observed within certain limits under such circumstances. It is seen in consequence that such agents are not sufficient means for controlling, compensating for, or eliminating the undesired phenomena referred to above.

We have ascertained that the undesirable phenomena accompanying the inflammation of combustible mixture are influenced, not only by the character and intensity of the igniting agent, but also by the time and manner of application of the igniting agent. Where an electric discharge is the igniting agent, this should be applied in the ideal case as a single direct discharge without oscillation, and for a very brief interval of time proportional to the rate of flame propagation in the explosive mixture. When using the conventional oscillating circuit it is possible to approximate substantially unilateral passage of an electric discharge by the use of means for limiting the number of oscillations and of a damping circuit for decreasing rapidly the intensity of the succeeding oscillation. In order that such means of ignition may be substantially equivalent to ignition by unilateral discharge, it is necessary that the time of ignition be limited to a maximum duration which is usually a small fraction of a second and depends upon the intensity of discharge, the frequency of oscillation and the degree of damping in the circuit, and the characteristics of the combustible mixture and the combustion chamber. For example satisfactory results may be obtained and the presence of shock waves avoided if the duration of ignition be 0.025 seconds covering 1.5 cycles of a 60-cycle damped discharge, when igniting hydrocarbon vapor-air mixtures at atmospheric temperature and pressure in a relatively large closed combustion chamber,

such as one 30 inches in length and 3 inches in diameter, which may be completely inflamed in 0.16 seconds after ignition. On the other hand, violent shock waves which will rupture the same apparatus are developed by simply increasing the number of discharges across the spark gap so as to occupy a time interval of about 0.15 seconds.

As the rate of reaction is increased by an increase in pressure or temperature, it is necessary to decrease proportionally the duration of contact between the explosive mixture and the electric igniting discharge. For example, the contact should be for about one ten-thousandth part of a second where the combustible mixture is of hydrocarbon vapor and air at a pressure upwards of 5 atmospheres and a temperature upwards of 200 degrees F.

In accomplishing combustion in accordance with the present invention, the combustible mixture is provided in the usual manner and brought to the desired condition of temperature and pressure without effecting ignition. This is then effected independently by suddenly applying an igniting agent, such as an electric spark directly as a substantially unilateral discharge for the desired brief interval of time. Where an electric spark is the igniting agent, any suitable electrical system may be employed for applying the spark where its character and duration are determined by the electric properties of the system. A revolving commutator in conjunction with a damping circuit has been found suitable for controlling the duration of the discharge in relatively slow burning mixtures such as hydrocarbon vapor and air at substantially atmospheric pressure.

In the accompanying drawing is illustrated a practical manner in which combustion is effected by an electric spark in accordance with the practice of the invention. Here 10 denotes an oven which is to be heated by the combustion that takes place in an elongated combustion chamber 11, here shown in the form of a sinuous pipe disposed near the top of the oven. This pipe, as shown in Fig. 2, has a valved connection 12 for admitting and discharging at will gaseous agents to and from the interior of the chamber.

Electric means for effecting ignition in the manner above indicated are shown at the left of the drawing in Fig. 2, where 13 denotes a commutator adapted to revolve at a relatively high rate of speed. This commutator is shown as provided with a contact segment 14 made to span a relatively short arc, which when revolved operates to reduce the time for the passage of the spark to the desired short interval. A conductor 15 leads from the commutator to an electrode 16 of a spark gap within the combustion chamber. The

other electrode 17 of this gap has a conductor 18 in series with an inductance coil 19 and the contact 20 which bears on the commutator 13 and is adapted to make contact 5 with the segment 14 when it sweeps under the same. This system is arranged to be supplied with electrical energy through the winding 21, which is inductively related to the winding 19, the winding 21 being connected to any suitable intermittent or periodic source of electric current.

While a discharge of suitable character and duration may be produced by an electrical system containing only inductance and 15 a commutator arranged for closing the circuit for but relatively brief intervals, other electrical systems may be employed. Figs. 3, 4 and 5 show exemplary forms of such other electrical systems which may be substituted for that shown in Fig. 2. In Fig. 20 33 an inductance 29 is shown in series with the commutator 13, a condenser 24 and a spark gap 26—27. Here the condenser is shunted by a relatively high resistance 25. The resistance, as is obvious, affects the 25 time constants of the circuit and operates to insure the desired brief discharge, which is employed in the practice of the invention.

In the arrangement shown at Fig. 4, an inductance 39 is shown in series with a commutator 13 and a spark gap 36—37. The gap here is shunted by a condenser 34 having in series therewith a high resistance 35 which attenuates this spark and also affects 35 the time characteristics of the discharge. Fig. 5 shows another system similar to that in Fig. 4, but differs therefrom in having a grounded connection 40 whereby a relatively constant spark characteristic is at all times insured; the complete discharge of the condenser 34 being accomplished outside of the spark gap with each revolution of the commutator prior to the recharging stage. The systems shown in Figs. 3, 4 and 5 are arranged to be supplied with electrical energy 45 through the windings 21 which are inductively related to the windings 29 and 39 respectively, the winding 21 being connected to any suitable intermittent or periodic 50 source of electrical current in a manner similar to that shown in and described in relation to Fig. 2.

In operation, the chamber 11 is filled with a combustible mixture at a desired pressure and temperature. The commutator 13 may be kept constantly revolving if desired, so that when it is desired to ignite the mixture the circuit containing winding 21 is closed. This effects the combustion desired.

60 While a closed combustion chamber has been illustrated as one to which the process of the present invention is applicable, it is apparent that the practice of the invention is not limited to such variety of combustion chamber, since a chamber through which the

gaseous agents are adapted to flow may be employed equally well. In such case, the rate of flow and the interval between the passage of the igniting spark are respectively so timed that the chamber is substantially filled with fresh mixture before firing.

70 Since certain changes in carrying out the above method and apparatus and in the constructions set forth, which embody the invention may be made without departing from its scope, it is intended that all matter contained in the above description or shown in the accompanying drawing shall be interpreted as illustrative and not in a limiting sense.

80 Having described our invention, what we claim as new and desire to secure by Letters Patent, is:

1. The method of igniting combustible mixture in combustion chambers without the 85 accompaniment of shock waves which comprises introducing a combustible mixture within a combustion chamber, and thereafter igniting the same by the direct application of an igniting agent for a period of time of the order of a ten thousandth part of a second.

2. The method of igniting combustible mixtures in combustion chambers without the 90 accompaniment of shock waves which comprises filling a combustion chamber with a combustible mixture at a desired pressure and temperature, and igniting the same by a substantially unilateral passage of an electric discharge for a relatively brief interval 100 of time.

3. The method of igniting combustible mixtures in combustion chambers without the 105 accompaniment of shock waves which comprises filling a combustion chamber with a combustible mixture at a desired pressure and temperature, and igniting the same by a substantially unilateral passage of an electric spark for a period of time not exceeding a small fraction of a second.

4. The method of igniting combustible mixture in combustion chambers without the 110 accompaniment of shock waves which comprises filling a combustion chamber with a combustible mixture at a desired temperature and at a pressure of several atmospheres, and igniting the same by a substantially unilateral passage of an electric spark of desired intensity for a period of time of the order of a ten-thousandth part of a 120 second.

5. The method of igniting combustible mixtures in combustion chambers without the 125 accompaniment of shock waves which comprises filling a combustion chamber with a combustible mixture containing hydrocarbon fuel vapors and air at a pressure of the order of several atmospheres and at a temperature below that of ignition, and igniting the same by a substantially unilateral 130

passage of an electric spark of desired intensity for a period of time of the order of a ten-thousandth part of a second.

6. Apparatus for effecting the ignition of combustible mixture without the accompaniment of shock waves, comprising in combination a combustion chamber having an inlet and a discharge, and electric means for igniting the mixture, said means being constructed to control the intensity of the igniting effect and to limit the time of its application to a desired period.

7. Apparatus for effecting the ignition of combustible mixture without being accompanied by shock waves, comprising in combination, a combustion chamber having an inlet and a discharge, and an electric system arranged to ignite the mixture in said chamber by the passage of an electric discharge, said system including electric elements for controlling the intensity of said discharge and an element for limiting the discharge to substantially unilateral passage for a period of time of the order of a ten-thousandth part of a second.

8. Apparatus for effecting the ignition of combustible mixture without being accompanied by shock waves, comprising in combination, a combustion chamber having an inlet and a discharge, and an electric system arranged to ignite the mixture in said chamber by the passage of an electric spark, said system including electric elements for controlling the intensity of an igniting spark and a commutator for limiting the spark to substantially unilateral passage for a period of time of the order of a ten-thousandth part of a second or less.

In testimony whereof we affix our signatures.
